UNITED STATES PATENT OFFICE

ARTHUR J. WALKER, OF OGDEN, UTAH

STENCIL

Application filed August 15, 1929. Serial No. 386,032.

My invention relates to stencils which while adapted for various uses, are particularly designed for the purpose of numbering houses in city streets. The device of my invention is adapted for use in applying the house number directly on the house, but it is preferably used for the purpose of applying the house number on the vertical face of the curb at the side of the street directly in front of the house. In this manner the identification of the house is made available from the street, and the number of the house may readily be ascertained from the curb instead of from the house, which in many instances stands back a considerable distance from the street or pavement. Under such conditions, when the house is located back from the street or pavement, great difficulty is experienced in reading the house number, especially at night.

The primary object of my invention is the provision of a stenciling device which is simple in construction and which may be manufactured at comparatively low cost of production; which may be manipulated with facility; and by means of which the house number or other insignia may readily be applied to a desired surface.

In carrying out my invention I utilize a stencil frame together with interchangeable stencil plates, and means are provided for rigidly locking the stencil plates in the frame for use. The frame is provided with a handle or guide plate which is used for retaining the frame in position against the surface upon which the insignia is to be produced.

My invention consists in certain novel combinations and arrangements of parts as will hereinafter be more fully set forth and claimed. In the accompanying drawings I have illustrated one complete example of the physical embodiment of my invention wherein the parts are combined and arranged according to the best mode I have so far devised for the practical application of the principles of my invention.

Figure 1 is a perspective view of my stenciling device showing it applied for use on a street curbing. Figure 2 is an enlarged transverse sectional view of the device. Fig-

ure 3 is a perspective view of one of the stencil plates.

In order that the utility of the device may be understood I have indicated in Figure 1 part of a street curbing C having the top face T, and the gutter is indicated at G. It will be understood that the house number 1235 is to be applied to the vertical face of the curb C. In applying the house number a space on the vertical face of the curb is first painted, as for instance a black background, and then the house number is applied on the background in a contrasting color. Thus the device is used in two different ways for the purpose of producing the house number.

In carrying out my invention I preferably fashion the parts from metal and I use a flat rectangular base plate or stencil frame 1 having an open longitudinally extending slot 2 and along the upper and lower edges of this slot are provided exterior grooved guideways 3 and 4. At the left ends of these guideways are provided stops 5, while the right ends of the guideways it will be understood are open. At the upper edge of the stencil frame 1 a handle plate or retaining plate 6 is hinged at 7. This plate is provided with concave or curved parallel edges 8 so that it may be fitted over the top face of the curb, and at the hinge joint as indicated at 9 in Figure 2 the edges of the stencil frame and the retaining plate are fitted together so that the two elements, when the joint is closed, are perpendicular one to another. By means of this guide plate or retaining plate 6, the stencil frame may be adjusted to desired position and there retained. Thus the operator may hold the plate 6 in the left hand while he paints with a brush in the right hand. While the stencil and the plate 6 are disposed at right angles in Figure 1 it will be seen that these parts are to be used while in vertical or horizontal alignment as indicated in Figure 2, and of course the parts may be disposed at various angles in order to bring the stencil frame parallel with and flush against the surface to be painted.

The guideways 3 and 4 of the stencil frame are adapted to receive interchangeable stencil plates indicated at 10. As best seen in

Figure 3 these plates are rectangular in form and provided with out standing flanges 11. The flanges are turned up from the right hand edges of the stencil plates and they terminate short of the top and bottom edges of the plate in order that the flanged plates may be slid along in the grooved guideways 3 and 4. It will be apparent that the flanges 11 are used as handles and are grasped between the thumb and finger for sliding the stencil plates in and out of operative position.

In Figure 1 I have shown four stencil plates and in addition I have shown a blank plate 10A which is similar to the stencil plates but from which the cut out is omitted. It will be understood that the number of stencil plates may be increased or diminished and the blank plates or filler plates 10A may be used where required, and these stencil plates and blank plates are all interchangeable for use.

When using the device the background is painted on the surface through the unobstructed opening 2. Then after the paint for the background has dried the number 1235 is painted or stenciled through the plates after the latter have been placed in position. These stencil plates are locked in position by means of a screw key 12 in the form of a bolt which is threaded in a nut 13 that is fixed at the right hand end of the upper grooved guideway 4. This bolt 12 extends through the nut and also through the guideway 4 and impinges against the last stencil plate or as in Figure 1 against the blank plate 10A. Thus by pressure on the succeeding flanges 11 of the stencil plates they are brought into close contact one with another and then the blank plate 10A is pressed close against the right hand stencil plate in order that the stencil plates may be held in proper position. Then by turning the key or bolt 12 the plates are all locked securely and rigidly in position in order that the painter may be free to quickly and properly apply the number to the surface. Of course the combinations or numbers to be used in the frame are changed whenever required and these changes may be accomplished with facility.

Having thus fully described my invention what I claim as new and desire to secure by Letters Patent is:

1. The combination in a stenciling device with a slotted frame having upper and lower guideways and end stops for said guideways, of a plurality of plates slideable in the guideways, said plates having edge flanges extending therefrom, a nut secured on one of the guideways, and a bolt in said nut adapted to impinge against one of the plates.

2. The combination in a stenciling device with a guide plate adapted to rest on the top surface of a curb, of a slotted frame hinged to the plate and adapted to lie against the

face of the curb, said frame having upper and lower grooved guideways, a stop at one end of the guideways, a plurality of stencil plates slideable in the guideways, edge flanges on said plates, and means at the opposite end of the guideways co-acting with a stencil plate for securing said plates in rigid position.

ARTHUR J. WALKER.
